United States Patent Office

Des. 185,693
Patented July 21, 1959

185,693

PHOTOGRAPHIC EXPOSURE METER

Yukihiko Asano, Tokyo, Japan, assignor to U.S. Photo Supply Co., Inc., Washington, D.C., a corporation of Delaware

Application July 15, 1958, Serial No. 51,792

Term of patent 14 years

(Cl. D61—1)

FIG. 4

FIG. 3.

FIG. 1.

FIG. 2.

FIG. 5.

FIG. 6.

Fig. 1 is a top plan view of a photographic exposure meter showing my new design.

Fig. 2 is a right side elevational view thereof.

Fig. 3 is a left side elevational view thereof.

Fig. 4 is a front end elevational view thereof.

Fig. 5 is a rear end view thereof.

Fig. 6 is a bottom plan view thereof.

The dominant features of my design reside in the portions shown in full lines.

I claim:

The ornamental design for a photographic exposure meter, as shown and described.
